UNITED STATES PATENT OFFICE.

HENRY P. CAMP, OF ALTON, ILLINOIS, ASSIGNEE TO WESTERN CARTRIDGE COMPANY,
OF EAST ALTON, ILLINOIS, A CORPORATION OF DELAWARE.

TARGET TRAP.

Application filed December 10, 1926. Serial No. 153,793.

This invention pertains to target throwing devices, and more particularly to a hand thrower for clay targets such as are used for trap shooting practice.

5 One of the objects of this invention is to provide a simple device by means of which a clay target can be thrown from the hand in an effective manner.

10 Another object is to provide such a hand target thrower by which the target may be delivered with a sharp whipping action.

15 Another object is to provide such a thrower which will cause the target to leave the thrower with a rotary or whirling movement.

Another object is to provide a target thrower which may be used with either the right or left hand for throwing a target.

20 Further objects will appear from the following description, taken in connection with the accompanying drawing, in which

Figure 1 is a front view of a target thrower embodying this invention;

25 Figure 2 is a right-hand side view of Figure 1;

Figure 3 is a section on line 3—3 of Figure 1;

Figure 4 is a section on line 4—4 of Figure 1;

30 Figures 5 and 6 are sections on lines 5—5 and 6—6, respectively, of Figure 1;

Figure 7 is a front view of a target thrower showing another embodiment of this invention;

35 Figure 8 is a right-hand side view of a portion of Figure 7; and

Figure 9 is a front view, similar to Figure 7, showing another embodiment of this invention.

40 Referring to the drawing, 1 designates a handle of wood or other suitable material, by means of which the device is manipulated. On the end of the handle 1 is mounted or formed a resilient extension 2, which may be constructed of a length of spring wire formed into a curl or loop 3. Rigidly formed or mounted on the end of the extension 2, and beyond the loop 3, is an arm 4. This arm is formed so as to provide top and bottom guides 5 and 6, spaced from each other so as to permit the flange 7 of the target 8 to pass between such guides. The arm 4 and its guides may be formed by bending the wire into the form shown in the figures; or it may be con-

structed of sheet metal suitably formed, or 55 by other means. There is thus provided a rigid arm 4 at the end of a flexible handle and extending in prolongation thereof.

Mounted on the arm 4 is a pivot support 9, which has pivoted thereto at 10 a second 60 arm 11. The arm 11 may be constructed of sheet metal or other suitable material and is pivoted so as to move in substantially the same plane as the guides 5 and 6. In the embodiment of Figure 1, the arm 11 has a channel form adapted to receive the target between its flanges. In Figures 7 and 9, the arm 11 is flat and arranged to provide a backing against which the target may rest. One

65 or the other of the arms 4 or 11 may be provided with an abutment 12, which is perforated to permit the passage therethrough of an adjusting rod 13. In the embodiment of Figure 1, the arm 11 has a channel form adapted to receive the target between its flanges. In Figures 7 and 9, the arm 11 is flat and arranged to provide a backing against which the target may rest. One

70 or the other of the arms 4 or 11 may be provided with an abutment 12, which is perforated to permit the passage therethrough of an adjusting rod 13. In the embodiment of Figure 1, the arm 11 has a channel form adapted to receive the target between its flanges. In Figures 7 and 9, the arm 11 is flat and arranged to provide a backing against which the target may rest. One

75 or the other of the arms 4 or 11 may be provided with an abutment 12, which is perforated to permit the passage therethrough of an adjusting rod 13. In the embodiment of Figure 1, the arm 11 has a channel form adapted to receive the target between its flanges. In Figures 7 and 9, the arm 11 is flat and arranged to provide a backing against which the target may rest. One

80 or the other of the arms 4 or 11 may be provided with an abutment 12, which is perforated to permit the passage therethrough of an adjusting rod 13. In the embodiment of Figure 1, the arm 11 has a channel form adapted to receive the target between its flanges. In Figures 7 and 9, the arm 11 is flat and arranged to provide a backing against which the target may rest. One

85 or the other of the arms 4 or 11 may be provided with an abutment 12, which is perforated to permit the passage therethrough of an adjusting rod 13. In the embodiment of Figure 1, the arm 11 has a channel form adapted to receive the target between its flanges. In Figures 7 and 9, the arm 11 is flat and arranged to provide a backing against which the target may rest. One

90 or the other of the arms 4 or 11 may be provided with an abutment 12, which is perforated to permit the passage therethrough of an adjusting rod 13. In the embodiment of Figure 1, the arm 11 has a channel form adapted to receive the target between its flanges. In Figures 7 and 9, the arm 11 is flat and arranged to provide a backing against which the target may rest. One

95 or the other of the arms 4 or 11 may be provided with an abutment 12, which is perforated to permit the passage therethrough of an adjusting rod 13. In the embodiment of Figure 1, the arm 11 has a channel form adapted to receive the target between its flanges. In Figures 7 and 9, the arm 11 is flat and arranged to provide a backing against which the target may rest. One

100 or the other of the arms 4 or 11 may be provided with an abutment 12, which is perforated to permit the passage therethrough of an adjusting rod 13. In the embodiment of Figure 1, the arm 11 has a channel form adapted to receive the target between its flanges. In Figures 7 and 9, the arm 11 is flat and arranged to provide a backing against which the target may rest. One

105 or the other of the arms 4 or 11 may be provided with an abutment 12, which is perforated to permit the passage therethrough of an adjusting rod 13. In the embodiment of Figure 1, the arm 11 has a channel form adapted to receive the target between its flanges. In Figures 7 and 9, the arm 11 is flat and arranged to provide a backing against which the target may rest. One

110 or the other of the arms 4 or 11 may be provided with an abutment 12, which is perforated to permit the passage therethrough of an adjusting rod 13. In the embodiment of Figure 1, the arm 11 has a channel form adapted to receive the target between its flanges. In Figures 7 and 9, the arm 11 is flat and arranged to provide a backing against which the target may rest. One

115 or the other of the arms 4 or 11 may be provided with an abutment 12, which is perforated to permit the passage therethrough of an adjusting rod 13. In the embodiment of Figure 1, the arm 11 has a channel form adapted to receive the target between its flanges. In Figures 7 and 9, the arm 11 is flat and arranged to provide a backing against which the target may rest. One

120 or the other of the arms 4 or 11 may be provided with an abutment 12, which is perforated to permit the passage therethrough of an adjusting rod 13. In the embodiment of Figure 1, the arm 11 has a channel form adapted to receive the target between its flanges. In Figures 7 and 9, the arm 11 is flat and arranged to provide a backing against which the target may rest. One

125 or the other of the arms 4 or 11 may be provided with an abutment 12, which is perforated to permit the passage therethrough of an adjusting rod 13. In the embodiment of Figure 1, the arm 11 has a channel form adapted to receive the target between its flanges. In Figures 7 and 9, the arm 11 is flat and arranged to provide a backing against which the target may rest. One

130 or the other of the arms 4 or 11 may be provided with an abutment 12, which is perforated to permit the passage therethrough of an adjusting rod 13. In the embodiment of Figure 1, the arm 11 has a channel form adapted to receive the target between its flanges. In Figures 7 and 9, the arm 11 is flat and arranged to provide a backing against which the target may rest. One

ment 19 into engagement with the rim of the target. The target is then resiliently held or clamped between the two arms. The operator, then grasping the end of the handle 1, 5 swings the device to the rear and then forwardly and upwardly with a quick whipping movement. During the acceleration of the device, the loop 13 permits the handle to flex under the force applied by the operator. Towards the end of the swing, the resiliency of 10 the loop 13 brings the arms forward with a sharp whipping action so as to force the target out of the thrower. In leaving the device the target slides along the guides 5 and 6 while 15 the frictional engagement with the abutment 19 retards that side of the target. Consequently, the target is released with a rolling movement which causes it to spin during its subsequent flight.

20 It will be seen that this invention provides a simple and inexpensive target throwing device, and one which is effective in action. The target is easily inserted between the arms and is securely held until the end of the throwing movement, when it is released with a 25 rotary movement. The nut 16 provides for adjustment of the tension of the arm 11, so as to adjust not only the friction at the abutment 19, but also the force with which the 30 target is held in the arms.

It is obvious that various changes may be made in details of construction without departing from the spirit of this invention; it is, therefore, to be understood that this invention is not to be limited to the specific details 35 shown and described.

Having thus described this invention, what is claimed is:

1. A hand target thrower, comprising, a flexible handle, an arm rigidly connected with 40 said handle and providing a guide for the target, a second arm pivoted on said handle adjacent said first arm and having a friction abutment adapted to engage the target, and means for tensioning said second arm, said 45 arms having target-engaging elements symmetrically formed with respect to the plane of the target.

2. A hand target thrower, comprising, a flexible wire handle having oppositely coiled 50 spring loops formed therein, and a target holder carried by said handle having its parts symmetrically positioned with respect to the plane of the target.

3. A hand target thrower, comprising, a 55 flexible handle, an arm rigidly connected with said handle and having a pair of guide rails symmetrically positioned with respect to the plane of the target and adapted to receive the target, and a second arm pivoted adjacent 60 said first arm and having a friction abutment tensioned to engage the target.

4. A hand target thrower, comprising, a flexible handle of wire, an arm on said handle formed of a wire looped back upon itself to 65 form parallel guide rails, and a second arm pivoted to said first arm and having a friction abutment tensioned to engage the target.

In testimony whereof I affix my signature this 19th day of November, 1926.

HENRY P. CAMP
